[**] Term: **14 Years**

The ornamental design for a pair of binoculars or similar article.

[21] Appl. No.: **930,109**

DESCRIPTION

[22] Filed: **Aug. 1, 1978**

FIG. 1 is a front view of a pair of binoculars or similar article showing our new design.

[51] Int. Cl. ..... **D16—06**

FIG. 2 is a bottom plan view thereof.

[52] U.S. Cl. **D16/133**

FIG. 3 is a left side view thereof.

[58] Field of Search **D16/58, 63, 133;**

FIG. 4 is a front view thereof.

350/145, 146, 75, 76, 36, 51, 71, 72

FIG. 5 is a top plan view thereof.

[56] **References Cited**

The characteristic feature of our design resides in the focusing control handle of the pair of binoculars which is formed with a plurality of spaced vertical indentations provided with a substantially horizontal slot extending across the front of said control handle.
